UNITED STATES PATENT OFFICE.

HOMER P. K. PECK, OF CINCINNATI, OHIO.

ARTIFICIAL EAR-DRUM.

SPECIFICATION forming part of Letters Patent No. 235,566, dated December 14, 1880.

Application filed October 7, 1880. (No model.)

To all whom it may concern:

Be it known that I, HOMER P. K. PECK, of the city of Cincinnati, and State of Ohio, have invented a new and useful Improvement in 5 Artificial Ear-Drums for the Relief of Deafness; and I do hereby declare that the following is a full, clear, and exact description thereof, reference being had to the accompanying drawings, and to the letters of reference marked 10 thereon.

In the drawings, Figure 1 represents a face view of the elastic disk; Fig. 2, a central longitudinal section of the appliance complete. Fig. 3 is a similar section with the elastic 15 disk detached. Fig. 4 is a central longitudinal section with a part of the stem broken away; and Fig. 5 represents the outline, size, and shape of the artificial tympanum as formed and used with my improvements for 20 adults.

The line *x* denotes a wire, which may be used when the appliance is withdrawn from the ear to remove any obstructions that might prevent the passage of air through the tubular stem *c*.

My invention relates to certain improvements in the artificial ear-drum of thin elastic material, which for many years has been used to restore the hearing of the deaf, especially 30 in cases in which the natural tympanum had been destroyed or punctured; and it consists in making the stem tubular, and in furnishing it with a single thin collar or flange, to which an elastic plate or disk, serving as an artificial 35 tympanum, is attached, and in constructing the latter of two pieces of thin elastic material, (like that class of rubber goods used in surgery for bandages,) which pieces are cemented together, so as to form an annular connection between them, leaving a central space 40 or portion detached, into which the metal collar at the end of the stem may be buttoned or inserted and retained firmly by first dipping the collar into elastic cement, as hereinafter 45 described.

The flexible elastic disks *a* *b* are cemented together, as shown in Fig. 4, and either one may be provided with a slit or button-hole, *f*, (see Fig. 1,) to allow the flange or collar *c* to 50 be inserted between them.

In Fig. 1 the central dotted circle denotes

the metal flange or collar *c*. The larger dotted circle denotes the smaller elastic disk *b*, which is cemented to the thin flexible tympanum *a*, and incloses the collar *c*. *c* denotes the tubular stem, preferably made of gold, about one-sixteenth of an inch in diameter and about one inch and one-fourth in length, provided with a ring, *d*, as a handle, to clasp between the thumb and finger for inserting the tympanum *a* into the auditory passage or tube of the ear, and for removing it, which should be done two or three times each week, for cleansing both the ear and the artificial tympanum. As heretofore made, the stem of the 55 artificial ear-drum has been a solid metal wire provided with two thin metal collars at one end, and an elastic tympanum or disk was secured between them upon the end of the stem, thereby exposing the metal collar at the 60 extreme end of the stem, which, when inserted in the auditory tube of the ear, was liable to come forcibly in contact with the natural tympanum and to injure it, and thereby to cause irritation and inflammation; and as there was 65 no provision for admitting air into the ear between the natural and the artificial tympanum while the latter was in use, it was required to be frequently removed entirely from the ear for the purpose of properly ventilating the 70 auditory passage and the parts of the interior of the ear excluded from the atmosphere by this 75 artificial tympanum.

By means of the double flexible disk *a* *b* the collar or flange *c* is perfectly cushioned, and 80 thereby prevented from injuring the delicate membranes of the ear, and by the provision of the tubular stem and perforated flexible tympanum *a* the partial withdrawal of the appliance within the auditory tube of the ear 85 will cause the air to be drawn in through the tubular stem and perforated disk *a*, and come in contact with the natural drum of the ear. Besides, the difficulty and pain caused by the withdrawal of the artificial tympanum as 90 heretofore constructed is obviated by permitting the air to enter back of the tympanum as it is withdrawn, and thereby preventing the partial vacuum produced by the removal of the old appliance from the ear.

An important feature of my invention consists in the provision of the double elastic

disk *a b*, provided with a slit or button-hole, *f*, which enables the person using the instrument to readily attach a new tympanum, *a*, to the stem *c* when, from use and continued 5 subjection to the influence of the natural temperature of the auditory tube, it has become frail and inefficient for the function for which it is intended.

Having fully described my invention, and 10 the manner of using the same, I claim as new and desire to secure by Letters Patent—

1. A tubular stem, *c*, in combination with a thin flexible disk or artificial tympanum, substantially as and for the purpose described.

2. The double disk *a b*, forming the artificial 15 tympanum, centrally perforated for the admission of air, and provided with a suitable opening or slit, *f*, for the insertion of a metal collar on the end of the tubular stem *c*, by which the latter is attached to the tympanum, 20 substantially as described.

H. P. K. PECK.
